(No Model.)

J. J. BLAIR.

REVOLVING CYLINDER ENGINE.

No. 331,939.

Patented Dec. 8, 1885.

UNITED STATES PATENT OFFICE.

JOHN J. BLAIR, OF CINCINNATI, OHIO.

REVOLVING-CYLINDER ENGINE.

SPECIFICATION forming part of Letters Patent No. 331,939, dated December 8, 1885.

Application filed April 15, 1885. Serial No. 162,356. (No model.)

To all whom it may concern:

Be it known that I, JOHN J. BLAIR, of Cincinnati, in the county of Hamilton and State of Ohio, have invented a new and Improved 5 Revolving-Cylinder Engine, of which the following is a full, clear, and exact description.

This invention relates to certain new and useful improvements in that class of engines in which the piston is fixed and the cylinder 10 revolves around the piston, and which are known as "revolving-cylinder engines."

The invention consists in various parts and details and combinations of the same, as will be fully set forth and described hereinafter.

Reference is to be had to the accompanying 15 drawings, forming part of this specification, in which similar letters of reference indicate corresponding parts in all the figures.

Figure 1 is a longitudinal sectional elevation of my improved revolving-cylinder engine. Fig. 2 is a cross-sectional elevation of the same on the line $x-x$ in Fig. 1. Fig. 3 is a cross-sectional view on the line $x'-x'$, Fig. 1. Fig. 4 is a cross-sectional view on the line $y-y$, Fig. 1. Fig. 5 is a cross-sectional view on the line $z-z$, Fig. 1. Fig. 6 is a longitudinal sectional elevation of the rolling valve.

The cylinder A is provided with the elliptical cavity B, slightly contracted at the middle, and having packing-strips B' at the middle. The cylinder surrounds the cylindrical piston C, which is in contact with the packing-strips B at diametrically-opposite points, and between which and the cylinder the two steam-chambers C' C' are formed. The piston is provided with two diametrically-opposite longitudinal grooves, D, for receiving the cylindrical rolling valves E, which rest against rollers F in grooves F', adjacent to the grooves D, packing-strips G resting against the rollers F. From the bottoms of the grooves D two apertures, D', lead to the central bore, H, of the piston in which the sliding valve J is arranged, which is mounted rigidly on a rod, I, 45 passing longitudinally through the middle of the piston, and provided with a longitudinal slot, I', through which a pin, J², passes, which is held in the part J' of the frame R, which is connected by the pin S with the cylinder, so as to cause the said frame R to revolve with the cylinder, thus causing the rod I and the

valve J, held on the same, also to revolve with the cylinder. The valve J is provided with two opposite segmental recesses, U', as shown in Fig. 2, in which the cut-off valves U are placed, whereby the said cut-off valves are revolved with the valve J; but the said valves can slide independently of the cut-off valves. A tube, K, is connected with the piston and divided by a partition, L, into two channels, 60 L' L', the former being the exhaust-channel and the latter the inlet-channel. The ends of the channels are in communication with hollow rings l on the tube K, the said rings being connected with the steam supply and exhaust pipes. The rod I passes through a stuffing-box, M, in the end of the tube K, and on the outer end of the rod I a disk, N, is mounted, on which two curved springs, N', are secured to project toward the end of the 70 tube K. A sleeve, P, surrounds the rod I between the plate N and the end of the tube K, and to jaws on the said sleeve two angle-levers, O, are pivoted, having their short outwardly-projecting shanks resting against the inner side 75 of the plate N, and their long shanks projecting toward the end of the tube K and carrying weights P'. The inner ends of the springs N' are secured to the levers O. A key, m, is secured in the rod I and in the sleeve P in such 80 a manner as to cause the sleeve P to revolve with the rod I, but to permit the rod to slide in the sleeve. The rolling valve E is provided in its end with a groove, E', for receiving its packing. The rod I is arranged to revolve in 85 a groove, s, in the partition L in the tube K. The operation is as follows: The steam passes through the channel L' into the hollow T of the piston, into the central bore, and from the same through the channels or ports D' and 90 grooves D into the spaces C' between the piston and the cylinder. The steam forces out the rolling valves E against the inner surface of the cylinder, and the steam, abutting against the said valves, acts on the sides of the cylinder and revolves it in the direction of the arrow a': As the cylinder revolves, the parts 95 in contact with the piston gradually move toward the rolling valve and press the said valve down into the corresponding groove, D, and then, after the parts of the cylinder in contact with the piston have passed off the rolling

valves, the steam forces the valves out again and the action takes place as described above.

The exhaust-steam passes through channels *t* (shown in dotted lines in Fig. 2) into the exhaust channel *L'*. As the rolling valves *E* roll on the pivoted rollers *F*, the friction is reduced very much. The valve *J* serves to regulate the quantity of steam admitted into the space between the cylinder and piston, and when moved in the direction of the arrow *b'*, Fig. 1, shuts more or less of the ports *D'*, (shown in dotted lines,) thus permitting only a small quantity of steam to pass into the space *C'*.

15 When the cylinder revolves too rapidly, the weights *P'* fly out, and their levers *P*, acting on the plate *N*, move the same in the direction of the arrow *b'*, Fig. 1, and move the valve *J* in the same direction, thus causing less steam to be admitted, whereby decreased speed is obtained. When the cylinder revolves slower, the weights *P'* swing back, and by means of the springs *N'* pull back the plate *N*, the rod *I*, and the valve *J* in the inverse direction of the arrow *b'*, thus admitting more steam into the spaces *C'*. The speed of the engine is thus regulated automatically by means of a very simple contrivance.

The cut-off valves *U* cut off the steam at whatever point desired.

Having thus described my invention, what I claim as new, and desire to secure by Letters Patent, is—

1. In a revolving-cylinder engine, the combination, with a fixed piston and a revolving cylinder surrounding it, of a cylindrical chamber in the piston, a sliding valve in the said chamber, a rod connected with the revolving cylinder and the sliding valve, a sleeve surrounding one end of the rod, weighted levers on the sleeve, and a plate on the end of the said rod, against which plate the ends of the weighted levers rest, substantially as herein shown and described.

45 2. In a revolving-cylinder engine, the combination, with a fixed piston and a revolving cylinder surrounding it, of a cylindrical cham-

ber in the piston, a sliding valve in the chamber, a rod connected with the sliding-valve and the revolving cylinder, the plate *N* on the end of the rod, the sleeve *P*, surrounding the rod, the weighted angle-levers *O*, pivoted on the sleeve, and the springs *N'* secured to the levers and to the disk *N*, substantially as herein shown and described. 55

3. In a revolving-cylinder engine, the combination, with the piston *C* and the cylinder *A*, of the sliding valve *J* in the bore of the piston, the rod *I*, having the slot *I'*, the frame *R*, connected with the cylinder, the pin *J'*, held in the frame *R* and passed through the slot *I'* of the rod *I*, and a governor on the end of the rod *I*, substantially as shown and described. 50

4. In a revolving-cylinder engine, the combination, with the fixed piston *C*, having grooves *D*, of the revolving cylinder *A* and the rolling valves *E*, substantially as herein shown and described. 65

5. In a revolving-cylinder engine, the combination, with the fixed piston *C*, having grooves *D*, of the revolving cylinder *A*, the rolling valves *E*, and the rollers *F*, pivoted adjacent to the grooves *D*, substantially as herein shown and described. 70

6. In a revolving-cylinder engine, the combination, with a fixed piston, *C*, of the revolving cylinder *A*, the sliding revolving valve *J*, having recesses *U'*, and the cut-off valves *U*, placed in the said recesses, substantially as 80 herein shown and described.

7. In a revolving-cylinder engine, the combination, with the fixed piston *C*, having grooves *D*, from which ports *D'* lead to the bore of the piston, of the sliding revolving valve 85 in the bore, a rod on which the sliding revolving valve is mounted, a governor connected with the said rod, and of the rolling valves *E*, substantially as herein shown and described.

JOHN J. BLAIR.
